PAGE 2

Fig. 4

Fig. 3

To all whom it may concern:

Be it known that I, Charles Joseph Fletcher, a citizen of the United States, residing at Franklin, in the county of Sussex and State of New Jersey, have invented a new, original, and ornamental Design for a Combination Airplane and Helicopter, of which the following is a specification, reference being had to the accompanying drawings, forming a part hereof.

Figure 1 is a side elevation view of a combination airplane and helicopter with the wheels in extended position embodying my new design;

Figure 2 is a top plan view thereof;

Figure 3 is a front elevation view thereof; and

Figure 4 is a perspective view thereof with the wheels retracted.

I claim:

The ornamental design for a combination airplane and helicopter, as shown.
